UNITED STATES PATENT OFFICE.

ELIZABETH CHESHIRE AND EDWARD CHESHIRE, OF CINCINNATI, OHIO.

BOOK-SEWING MACHINE.

SPECIFICATION forming part of Letters Patent No. 317,507, dated, May 12, 1885.

Application filed May 24, 1883. (No model.)

To all whom it may concern:

Be it known that we, ELIZABETH CHESHIRE and EDWARD CHESHIRE, both citizens of the United States, and residents of Cincinnati, in the county of Hamilton and State of Ohio, have invented certain new and useful Improvements in Book-Sewing Machines, of which the following is a specification.

Our invention relates to improvements in machines for sewing books; and it consists, in the first part, of a signature-feeding table or carriage, in combination with a needle carriage or frame, both carriages being mounted upon a suitable frame in such a manner that they are adapted to advance toward each other and at the point of meeting perform the sewing operation by means of an ordinary shuttle and suitable driving mechanism.

Our invention further consists in the combination, with the frame carrying the needles for sewing the ordinary "hand-stitch," of two frames carrying needles to sew the "kettle-stitch," the kettle-stitch frames being mounted and moving on ways or bars within the said hand-stitch frame.

Our invention further consists in the combination, with the signature-feeding carriage, of a toothed plate adapted to support the fold of the signature and to receive the needles on the needle-frames between the teeth of said plate during the sewing operation.

Our invention further consists in the combination, with the signature-feeding carriage having the toothed plate, of presser-heads or bumpers, which sustain the hanging leaf or leaves of the signature during the sewing operation, and simultaneously compress the previously-sewed signatures into book form.

Our invention further consists in the combination, with the signature-feeding carriage, of laterally-adjustable shuttle-raceways having a gap or an intervening space between the said raceways which is capable of being lengthened or shortened to accommodate different-sized signatures.

Our invention further consists in the combination, with the needle-carrying frames, of a frame pivotally mounted at its ends on the frame of the machine and adapted to suitably take up the slack that occurs in all the twines, and a series of spring-plates, one for each of said twines, for exerting the proper tension on said twines during the sewing operation.

In the construction of our machine we prefer to use, in connection with the above-described mechanism, downwardly curved or bowed needles, which are mounted on said needle-carriages and dip in such a manner that the twines, which pass through the eyes in their points to a fastening-point beneath the needle-frames, leave a space for the passage of the shuttle which carries the sewing-thread. Other features of our invention will be fully set forth in the following description of the accompanying drawings, and afterward specifically claimed.

Figure 1 is a side elevation of the machine embodying our invention, showing the feeding-frame, signature, shuttle, and needle-frame in position in the act of sewing. Fig. 2 is a central sectional elevation of the same with the feeding-carriage in position for receiving a signature for sewing, and the needle-frames, retracted in the rearward position, at rest. Fig. 3 is a front elevation of the machine. Fig. 4 is a plan view of the machine. Fig. 5 is an enlarged detail sectional elevation of broken-off portions of the feeding-carriage and needle-frame, showing one of the needles and the shuttle and twine in the act of sewing a signature. Fig. 6 is a detail plan view of the needle-frame, showing one of the kettle-stitch frames in the forward sewing position, and the other frame, in its rearward position. At rest. Fig. 7 is an elevation of the front end of the needle-frames shown in Fig. 6. Fig. 8 is a skeleton view of the usual "hand-made" stitch, which is best adapted to the kettle-stitch made in our machine.

A A' represent the opposite side supporting frames of the machine, being secured together by cross-bars *a a*.

B represents the main driving-shaft mounted in bearings on side frames, A A', and furnished at one end with tight and loose pulleys *b b'*.

C represents a gear-wheel mounted on shaft B, and engaging a larger gear, D, keyed to the shaft E. Shaft E is mounted in bearings on side frames, A A', and is provided at its opposite ends with cams *e e*, which alternately drive the picker-staffs F F, pivotally mounted, as customary in looms, at their lower ends in boxes on the base of said side frames.

F' F' represent spiral or coiled springs stretched between the picker-staffs and the side frames, A A', to operate said picker-staffs

when depressions *f* in cams *e* come opposite them.

c represents an eccentric keyed to shaft *B*, and *d d'* are cams keyed to shaft *E* in such a manner as to project in opposing directions, which will be hereinafter referred to.

G represents a reciprocating carriage or frame, upon which the respective signatures are fed into the machine and supported during the sewing operation. The opposite ends of carriage *G* move in guides *g g* constructed on the inner faces of side frames, *A A'*.

g' represents ears on the bottom of carriage *G*. *G'* are links pivotally connecting ears *g'* with

levers *H*, which levers are rigidly connected at their lower ends to a shaft, *H'*. Shaft *H'* journals in bearings *h* on side frames, *A A'*. Bearings *h* are in multiple, as shown, so that the shaft *H'* can be arranged higher or lower, as desired, and thereby shorten or lengthen the stroke of the feeding carriage for different-sized signatures.

I represents an arm keyed at one end to shaft *H'*, and projecting therefrom into the path of motion of the eccentric *c* upon driving-shaft *B*.

g'' represents guides on the top of carriage *G*, between which the signatures pass and rest.

J is a plate projecting from the forward end of feed-table *G*. Upon the edge of plate *J* the fold of the respective signatures lies with one leaf or leaves on one side of the fold lying on the table, and the leaf or leaves on the other side of the fold hanging down.

j represents teeth on the forward end of plate *J*, making it of comb configuration.

J' J' are presser-heads on the forward corner ends of table *G*.

K represents a temporary table or rack arranged above the feeding-carriage in its re-treated position, and upon which table a number of signatures are placed in an open condition, with the back of their folds upward, as shown in Figs 1 and 2.

L L' represent laterally-adjustable raceways for supporting the shuttle *L'* in position at the end of its stroke, to receive the blow of either of the picker-staffs which pass upwardly through them. These raceways *L L'* are ar-

50 ranged, as customary, in looms, projecting outwardly from the side frames, *A A'*, with an intervening space between them; but in this machine they are preferably mounted upon brackets *L'' L''*, which are secured to said side

55 frames, and are attached adjustably to said brackets by bolts *ll* which pass through slots made in the brackets. The adjustability of race ways *L* permits their movement inwardly or outwardly to accommodate signatures of different sizes placed in the space between them.

M represents a horizontally-reciprocating frame, upon the forward end of which sewing-needles *m* are secured.

60 *m' m''* are studs or pins projecting from the opposite side ends of needle-frame *M*. The pins *m'* are at the rear of the said needle-

frame, and travel in straight horizontal slots *n* made in the frames *A A'*, and the pins *m''* are at the front end of said needle-frame, traveling in curved slots *n'* made in said side frames forward of slots *n*. The curved form of slots *n'* insures the proper downward movement of the needle frame, so that a dip or fall from a straight line of the points of the needles *m* 75 will occur at the time they enter the fold of the signature, and thus avoid their contact with the leaves of the signature.

M' M' are two frames mounted upon rods *M''* within the needle-frame *M* so as to reciprocate therein.

N is a needle projecting from the forward end of both frames *M'*, to form, in the sewing operation, what is known as the "kettle-stitch." The needles *m* and *N* are all constructed alike. The form of needles we prefer to use in our machine is shown full size in Fig. 5. They are curved or turned slightly downward, so as to form an opening between them and the twine, which passes through an eye, *N'*, in their points, for the passage of the shuttle *L'*.

N² represents a groove constructed along the upper face or convex portion of the needle from its fastening-shank to the eye *N'*. The 95 twine rests in the groove *N²*, so that that part of it passing along the groove between the shank and the eye of the needle will not drop on either side to come in contact with the shuttle to become entangled with the shuttle-thread. The twines passing from the eyes *N'* beneath the needles form a part of the race-way for the passage and support of the shuttle, similar to the warp-threads in a loom.

O O represent vertical levers pivoted intermediate their ends to the cross-bars *a'* of the side frames, their upper ends being slotted to receive the pivotal pins *o* on the outer ends of arms *O'*, attached to the needle frames *M'*. The lower ends of levers *O* project into the path of motion of the cams *d d'* on shaft *E*, which cams, being on said shaft in opposing directions, alternately come in contact with levers *O*, and thereby move the needle-frame *M* forward, a retractile spring, *o'*, being provided in connection with both levers to move the said needle-frame rearward and hold the lower ends of said levers in contact with said cams. The upper ends of the alternately oscillating levers *O* being pivotally connected with arms *O'* on the needle-frames *M'*, and the frames *M'* reciprocating within frame *M*, the said frames *M'* are alternately brought forward and at the same time advance the said frame *M*, with its needles, to perform the operation of sewing. The forward end of frame *M* follows the motion of the pins *m''* in curved slots *n'*, as stated heretofore, thus giving the proper direction of motion to the needles in their passage into and from the fold of the signature. The spaces between teeth *j* of plate *J* of the feeding-carriage permit the entrance of the needles on the meeting of said feeding-carriage and the needle-frames, for the

close working of the operative parts of the machine.

In connection with the sewing devices above described we provide a tension and take-up mechanism for controlling the working of the twines, the preferred form of which mechanism we will now describe.

P represents a trough or box for holding the balls of twine P''. The twine for each of the needles passes from trough P through an eye, p, in each of the spring-plates p', which plates are attached in position upon cross bar P' of the main frame by tension-regulating thumb-screws P''. It then passes from said eyes p under the free end of plates p' to an oscillating take-up frame, Q. Frame Q is preferably an open rectangular one, and is centrally mounted at its opposite ends upon pivots q, which journal in vertical brackets Q' on the needle frame M.

R represent studs at the rear corners of frame Q, projecting into curved slots r made in the side frames, A A', and travel therein to rock-frame Q on its pivots in the movements of said needle-frame. The twine passes from the spring-plates p' under the rear bar of the take-up frame Q, and thence through perforations r' in the forward bar of said frame Q. From perforations r' the twines pass through eyes in the forward end of needle-frame M to the shanks of the needles; thence along the grooves in the needles to and through the eyes in their points, and thence beneath the needles rearwardly, with their ends secured to a cross bar or board, S, against which the folded ends of the signatures rest while the book is forming.

T represents pendant arms secured to cross-bar S, against which the sewed signatures rest while the book is forming.

T' represents an adjustable nut or gage on the arms T, for supporting the lower ends of the signatures.

In the operation of the machine the signature is fed, as shown in Fig. 2, from the pile on table K. Motion being imparted to the driving shaft, the feeding-carriage, with the said signature, is advanced toward the center of the machine, and at the time it reaches its limit of motion the needle-frame, which has been slowly advancing, meets it simultaneously, the needles with their contained twines passing through the fold of the signature. At the moment the needle-frame has approached its limit of motion the shuttle is driven across the machine through the twines and forming a loop with four of them, as shown, one being the end or kettle stitch.

The presser-heads on the feeding-carriage, when in the position shown in Fig. 5, serve to pile up the sewed signatures closely together on the twines stretched from the cross-bar S, and hold the signature firmly in place during the sewing operation.

On the retraction of the feeding-carriage and needle-frame to their normal positions, or at rest, the leaf or leaves of the signature rest

ing upon the table of the feeding-carriage drop into place against the other leaf or leaves, and the feeding and sewing operation is continued as before.

We claim—

1. In a book sewing machine, the signature-feeding carriage G, in combination with a needle carriage or frame, M M', both carriages being mounted upon a suitable frame, substantially as described, so that they advance toward each other and at the point of meeting perform the sewing operation by means of an ordinary shuttle and suitable driving mechanism, substantially as herein set forth.

2. A book-sewing machine composed, substantially, of a horizontal reciprocating signature-feeding carriage, G J j J', horizontally-reciprocating needle-frames M M', and a shuttle, L', with its customary driving mechanism, the said carriage G and needle-frames M M' being mounted upon a frame, and adapted to operate in the manner and for the purpose specified.

3. In a book-sewing machine, the combination, with the needle-frame M m of the kettle stitch needle-frames M' M' N, moving on ways or bars within said frame M, and adapted to operate substantially as herein set forth.

4. In a book-sewing machine, the combination, with the horizontally-moving signature-carriage G, of a toothed or comb-shaped plate, J j, adapted to support the signature in an open condition with one leaf thereof lying on the table, the other suspended vertically and its fold against the toothed edge of said plate, and to provide unobstructed passages for the sewing-needles on the meeting of the feeding and needle frames, substantially as herein set forth.

5. In a book-sewing machine, the feeding-carriage G, having the toothed plate J j, in combination with the presser-heads or bumpers J' J', which sustain the hanging leaf or leaves of the signature during the sewing operation, and simultaneously compress the previously-sewed signatures, substantially as herein set forth.

6. In a book-sewing machine, the combination, with the signature-feeding carriage G, of the laterally-adjustable raceways L L, having a gap or intervening space between said raceways which is capable of being lengthened or shortened to accommodate different sized signatures, substantially as herein set forth.

7. In a book-sewing machine, the combination, with the needle-carrying frames M M', of the open rectangular frame Q, pivotally mounted on the main frame of the machine and adapted to suitably take up the slack in the twines, and a series of tension-plates, p p' P'', one for each twine, substantially as and for the purpose specified.

8. In a book-sewing machine, the combination, with the needle-frames M M' m N, of pins or studs m' m'', moving in slots or ways,

n n' on the main frame, the pins *m'* moving in the straight slots *n*, and the pins *m''* moving in irregular or curved slots *n'*, to impart the proper downward motion or dip to the 5 needles as they pass through the fold of the signature, substantially as and for the purpose specified.

In testimony whereof we have hereunto set our hands.

ELIZABETH CHESHIRE.
EDWARD CHESHIRE.
